(57) **CLAIM**

The ornamental design for a set of keys for a handset having an illuminating region, as shown and described.

DESCRIPTION

FIG. 1 is a front view of a set of keys for a handset having an illuminating region showing our new design, wherein the illuminating region is not illuminated;

FIG. 2 is a front perspective view thereof;

FIG. 3 is an enlarged front view thereof;

FIG. 4 is an enlarged front perspective view thereof;

FIG. 5 is a front view of a set of keys for a handset having an illuminating region showing our new design, wherein the illuminating region is in an illuminated state;

FIG. 6 is a front perspective view thereof;

FIG. 7 is an enlarged front view thereof; and,

FIG. 8 is an enlarged front perspective view thereof.

The broken line of the square button that is shown within the claimed area defines an unclaimed region. The broken lines shown in FIG. 6 and FIG. 8, adjacent to the wall of the claimed button, represent the bounds of the claimed design, while all other broken lines are directed to environment and are for illustrative purposes only. None of the broken lines form a part of the claimed design. The radiating lines indicate illumination. The dark shading in the area just outside the central broken line square in FIGS. 1–4 compared to the same region shown unshaded in FIGS. 5–8 indicates a contrast in appearance between lit and unlit regions, and does not depict any particular color, texture, or material.
